(57) **CLAIM**

The ornamental design for a roof for a vehicle, as shown and described.

DESCRIPTION

This application is related to the following co-pending application, of the inventors, filed on even date herewith: Application Ser. No. 29/287,949, entitled “Vehicle, Toy, and/or Other Replicas”.

FIG. 1 is a left, front perspective view of a roof for a vehicle according to our novel design, the right, front perspective view being mirror symmetrical;

FIG. 2 is a left, rear perspective view thereof, the right, rear perspective view being mirror symmetrical;

FIG. 3 is a top view thereof;

FIG. 4 is a left side view thereof, the right side view being mirror symmetrical;

FIG. 5 is a front view thereof; and,

FIG. 6 is a rear view thereof.

In the drawings, the broken lines shown the boundary of a roof for a vehicle and form no part of the claimed design.
